UNITED STATES PATENT OFFICE.

JENNIE F. HOBBS, OF BRIDGEPORT, CONNECTICUT.

CAR-TRUCK.

SPECIFICATION forming part of Letters Patent No. 694,473, dated March 4, 1902.

Application filed September 13, 1901. Serial No. 75,276. (No model.)

To all whom it may concern:

Be it known that I, JENNIE F. HOBBS, a citizen of the United States, and a resident of Bridgeport, in the county of Fairfield and State of Connecticut, have invented certain new and useful Improvements in Car-Trucks, of which the following is a specification.

My invention relates to an improvement in car-trucks; and it consists in certain details of construction, to be more fully set forth in the following specification.

To enable others to understand my invention, reference is had to the accompanying drawings, in which—

15 Figure 1 represents an upper plan view of the truck with two of the antifriction-roll housings uncovered; Fig. 2, a side elevation looking in the direction of arrow *a* of Fig. 1, also vertical section of one of the antifriction-roll 20 housings. Fig. 3 is an end elevation through line *b b* of Fig. 1. Fig. 4 is a section of the truck through line *c c* of Fig. 1, showing the car-elevating screw raised against a dotted line representing the lower edge of a car. 25 Fig. 5 is a detail side elevation of one of the car-wheels with its removable axles therein.

Its construction and operation are as follows:

The side frames have the double walls 1, 30 2, 3, and 4, and between them are located the car-wheels 5, 6, 7, and 8. These wheels are removably secured to the short axles 9, 10, 11, and 12, which axles are journaled in the boxes 13. (Shown at Figs. 2 and 3.)

35 14, 15, 16, 17, 18, 19, 20, and 21 are housings attached to the side frames, and within them are located the antifriction-wheels 22, adapted to run against the upper surface of the car-axles, one on each side of each of the 40 car-wheels. As each antifriction-wheel is alike, the same figure of reference will answer for all. Each of said wheels is rigidly mounted on the short axle 23, journaled in the side frames of the truck and in the housings. 45 These wheels also serve to convey the oil from the boxes 24, (see particularly Fig. 2,) through the hole 25, to the axles of the car-wheels, against which, as before mentioned, the wheels 22 run. These wheels serve to convey the oil in small quantities onto the car-axles, and from thence it will work into the boxes 13 in sufficient quantities to keep that

portion of the axle in said boxes well lubricated.

26 are sliding covers for the oil-boxes 24. 55

27 is a depressible cross-piece suspended on springs 29, 30, 31, and 32. Two of these springs—viz., 28 and 32—rest on the cross-bars 33 and 34, which bars are supported on the side frames of the truck. The other 60 springs rest on the lower cross-piece 35, also supported in said side frames, and the extension-pieces 1^a and 3^a, Fig. 4. The body of the car is adapted to rest on the cross-piece 27, and the springs serve to keep the car level 65 when passing around a curve or where the track is uneven.

36 is an elevating-screw adapted to operate in a threaded hole in the projection 37 of the lower cross-piece 35. This screw is adapted to raise the car off the track for the purpose to be hereinafter more fully described. 70

The axles of the car-wheels are adapted to be removed whenever it becomes necessary to replace an old or broken wheel with a new 75 one. Therefore the central part 38, Fig. 5, of the axle is larger than the projecting ends 9, so that it is only necessary to drive the axle back far enough to disengage this central portion, when the remainder of the axle 80 can be slipped back and the wheel lifted out and replaced by another without running the car to the repair-shop. It will, however, be understood that the first step in the operation of putting in a new wheel is to elevate 85 the end of the car over the truck needing repairs.

The dotted line 39 represents, as before stated, the lower edge of the end of a car partly raised by the elevating-screw. 90

39^a is a recess in the lower edge of the car and is deeper than the thickness of the head of the said bolt, so that when the car rests on the cross-piece 27 it will give with the springs under said cross-piece without engaging with 95 the head of the elevating-screw. The end is lifted sufficient to allow a wheel to be lifted up between the side frames and over the top of the same.

40 are removable plates that prevent accidental end play of the car-axles. 100

To further assist in maintaining the equilibrium when rounding curves or passing over an uneven track, the side frames are joined at

their ends by the bars 41 and 42. Blocks 43 are rigidly secured to said side frames, while the bolts 44 enable the truck to rock side-wise independent of the end bars. The short car-axles also enable the car to turn sharp curves much better than the present construction, where both wheels are secured to the same axles. It will also be observed that (see Fig. 2) the top of the housings inclosing the antifriction or oiling wheels are removable in case it should become necessary to get at the interior.

Having thus described my invention, what I claim as new, and desire to secure by Letters Patent, is—

1. The combination, in a car-truck of the character described, of the side frames 1, 2, 3 and 4, independent car-wheels having short axles located between said frames and journaled therein, antifriction-wheels adapted to run on said axles, housings embracing said antifriction-wheels, housings inclosing each of said wheels, an overlying oil-receptacle on each housing, means whereby the oil is communicated to said wheels and transmitted by them to the axles of the car-wheels, for the purpose set forth.

2. The combination, in a car-truck, of the character described, of parallel side frames, independent car-wheels having short axles within said frames, removable means to prevent end movement of said axles, said axles adapted to be removed and the wheels lifted

out of said frames, means for elevating the car preparatory to such removal, for the purpose set forth. 35

3. The combination, in a car-truck, of the character described, with the side frames, of a depressible cross-piece to support the car, a second cross-piece below the first, springs 40 interposed between the two cross-bars pivotally supported to the ends of the side frames, whereby the equilibrium of the car is maintained under all circumstances, for the purpose set forth.

4. The combination, in a car-truck, of the character described, of the parallel side frames, independent car-wheels having removable axles, an upper depressible cross-piece adapted to support a car-body, combined with a lower 50 cross-piece, interposing springs, an elevating-screw adapted for raising one end of the car for the purpose of removing a wheel and replacing the same, cross-bars pivotally supported to the ends of said side frames so that, 55 in combination with said springs, the equilibrium of the car is maintained, for the purpose set forth.

Signed at Bridgeport, in the county of Fairfield and State of Connecticut, this 12th day 60 of September, A. D. 1901.

JENNIE F. HOBBS.
